[57] CLAIM

The ornamental design for a combined coffee maker and liquid heater/dispenser, as shown and described.

DESCRIPTION

FIG. 1 is a front perspective view of a combined coffee maker and liquid heater/dispenser embodying my new design;

FIG. 2 is a top plan view thereof;

FIG. 3 is a front elevational view thereof;

FIG. 4 is a left side elevational view thereof, the side opposite being a mirror image;

FIG. 5 is a rear elevational view thereof; and

FIG. 6 is a bottom plan view thereof.
